CLAIM

The ornamental design for a blood glucose meter, as shown and described.

DESCRIPTION

FIG. 1 is a perspective view of a blood glucose meter; FIG. 2 is a front view of the blood glucose meter of FIG. 1; FIG. 3 is a back view of the blood glucose meter of FIG. 1; FIG. 4 is a left view of the blood glucose meter of FIG. 1; FIG. 5 is right view of the blood glucose meter of FIG. 1; FIG. 6 is top view of the blood glucose meter of FIG. 1; and, FIG. 7 is bottom view of the blood glucose meter of FIG. 1. The broken line drawings of electrical connectors and battery compartment are for illustrative purposes only and form no part of the claimed design.
